UNITED STATES PATENT OFFICE

AMOS R. MORRIS, OF ANN ARBOR, MICHIGAN.

FOLDING MAP OR CHART.

Application filed June 16, 1927. Serial No. 199 297.

This invention relates to folding maps or charts, and the object of this invention and wherein it is believed to be superior to similar folders within the knowledge of this 5 applicant, is in the form and folding of the map or chart in relation to the form and attachment of the folding cover-backs to secure a maximum of accessibility with a minimum of unfolding. The advantages 10 following from the construction and arrangement of the parts of this invention as herein set forth are:—

1. Any part of the map is readily accessible.
- 15 2. After the angular folds have been extended, a single opening movement permits the examination of any section.
3. Two sections are laid open by taking hold of the two cover-backs.
- 20 4. A cover index map may be provided externally on either cover-back to enable the user to find readily the section desired without unfolding.
5. The cover-backs may carry detail maps 25 of cities or special sections of any locality arranged in order of the sections of the folded map.
6. The map constructed in accordance with this invention becomes a double faced map 30 by printing another map on the reverse side.
7. With a double face map the inside fold of the cover-backs rests between two of the sections of the map.

The special construction and arrangement 35 of the parts of this invention are illustrated in the accompanying drawings, of which:—

Figure 1 represents a plan view of all parts assembled and unfolded.

Figure 2 is an edgewise view of all parts 40 after the body portion has been folded once longitudinally, and shows the various portions before being closed together.

Figure 3 is an end view of all parts folded 45 into final form with all parts folded together.

Throughout this description and drawings the same number is used to refer to the same part.

The body of the map or chart 1 may be 50 folded transversely after being folded longitudinally, the longitudinal crease or line of folding is marked 2, and the transverse lines are designated by the numeral 3.

The cover-backs 4 and 5 are located at 55 diagonally opposite corners of the body 1. They are foldable extensions, and may be

made of material heavier than that of the body for stiffening and protective purposes and to form hand-holds or supports whereby the map may be conveniently and firmly held 60 in the hands when unfolded for use, without any of the face of the map being covered or hidden by the hands. It will be noted that each cover-back, such as the cover-back 4 may comprise a plurality of folding portions 65 6 and 7. This invention is not limited to any particular number of folds or thickness of material employed.

Considering Figure 2 it will be noted 70 that the cover-backs are now at the ends of the angularly folded strip made by giving the body 1 a single longitudinal fold, and in closing the folds together the cover-backs form the external pages of the whole.

It is desired here to call attention to the 75 fact that while the cover-backs are illustrated as composed of two-page equal leaves, it is not necessary that the portion 7 of the cover-back 4, and the corresponding portion of cover-back 5 shall be of equal extent with the first portion of the cover-back, but the portion 7 may terminate at the point marked X, and thus clear the entire back of the body 1 when the map or chart is reversed or 80 reversely folded.

The operation of this invention is believed 85 to be plainly discernible from the foregoing explanation and the accompanying drawings. Attention is asked to the fact that when the map is spread open as illustrated in Figure 1, the cover-backs are in position to exhibit any index data or other information printed thereon, to the person studying the map. That statement obviously holds good for either side of the map. When the whole is 90 folded into its final shape as set out in Figure 3, it may be of such size as to be readily placed in the pocket, although this invention is in no sense limited to pocket maps.

Having now described this invention, and 100 explained the mode of its operation, I claim:—

1. A folding map or chart, having a rectangular body portion adapted to be folded transversely and longitudinally, and stiffening extensions secured to diagonally opposite corners constructed and arranged to form the external pages when the whole is folded.

2. A folding map or chart, having a rectangular body portion adapted to be folded transversely and longitudinally, and fold-

able stiffening extensions secured to diagonally opposite corners of the said body and arranged to form the external pages when the whole is folded.

5. 3. A folding map or chart, having a body portion constructed to be folded transversely and longitudinally, and foldable two-leaf extensions secured to diagonally opposite corners of the said body, the said extensions forming cover-backs, and one of said extensions being arranged with its leaves directly together when the whole is folded, and the other extension including between its leaves a folded portion of the said body when the whole is folded.

10. 4. A folding map or chart, having a body portion constructed to be folded transversely and longitudinally, and foldable two-leaf extensions at diagonally opposite corners of said body, said extensions when folded forming cover-backs, one of said extensions being arranged with its leaves directly together when the whole is folded and having one leaf integrally attached to one corner 20 fold of the body portion, whereby said corner fold is stiffened, and the other extension including between its leaves the corner fold diagonally opposite the first named fold, the corner fold between said leaves 25 being integrally attached to one of said 30

leaves, whereby this corner fold is also stiffened.

5. A folding map or chart, having a body portion constructed to be folded into relatively small compact form, and foldable 35 two-leaf extensions of heavier material than the body of the map, arranged at diagonally opposite corners of said body portion, one of the leaves of said extensions being integrally secured to the adjacent corner of 40 the body portion, and the other leaf projecting laterally from said corner, when the leaves are unfolded, said laterally projecting leaves forming hand-holds, whereby the map may be conveniently and firmly held 45 in the hands when unfolded for use.

6. A folding map or chart, having a body portion constructed to be folded into relatively small compact form, and foldable 50 two-leaf extensions of stiff material secured to diagonally opposite corners of said body, said extensions when they and the map are folded forming separate and independent cover backs entirely disconnected from each other and which when the map is unfolded 55 for use provide hand-holds, whereby the map may be conveniently and firmly held.

In testimony whereof I affix my signature.

AMOS R. MORRIS.
